No. 793,049.

PATENTED JUNE 27, 1905.

J. BUFFELEN.
COLUMN CLAMP.
APPLICATION FILED APR. 20, 1903.

UNITED STATES PATENT OFFICE.

JOHN BUFFELEN, OF MILWAUKEE, WISCONSIN.

COLUMN-CLAMP.

SPECIFICATION forming part of Letters Patent No. 793,049, dated June 27, 1905.

Application filed April 20, 1903. Serial No. 153,378.

To all whom it may concern:

Be it known that I, JOHN BUFFELEN, a subject of the Queen of the Netherlands, residing at Milwaukee, in the county of Milwaukee and State of Wisconsin, have invented certain new and useful Improvements in Column-Clamps, of which the following is a specification, reference being had to the accompanying drawings, forming a part thereof.

10 This invention relates to clamps for holding the staves or sections of wood columns together and in place while they are being glued. Its main objects are to facilitate assembling and gluing the staves or sections of 15 wood columns and to improve the construction and operation of clamps for this purpose, making them readily adjustable for application to columns of different sizes and to different parts of tapered columns.

20 The invention consists in certain novel features of construction and in the peculiar arrangement and combinations of parts, as hereinafter particularly described, and pointed out in the claims.

25 In the accompanying drawings like letters designate the same parts in the several figures. Figure 1 is a plan view and horizontal section on the line 1 1, Fig. 3, of my improved clamp as applied to a column. Fig. 2 is a 30 plan view of the block to which one end of the flexible clamping-band is attached and in which the clamping-lever is fulcrumed. Fig. 3 is a side elevation of the clamp, the lever extension being removed and the handle of 35 the detachable arm on the clamping-block broken away; and Fig. 4 is a detail view showing the adjustable connection between the two parts or sections of the clamping-band.

40 *a* is a recessed block having one face fitted to bear against one face of a column and preferably made, as shown in Fig. 1, to approximately fit over the corner or angle formed by two adjoining staves or sections.

45 *b* is a lever having a recessed head *c*, which is fulcrumed to or pivoted in the block *a* on a pin *d* passing vertically through the recess in said block. The lever-head *c* is formed or provided on one side with ratchet-teeth *e*, ar- 50 ranged concentric with the pivot-pin *d*, and

a pawl *f*, pivoted at one end on a pin *g*, passing vertically through the recess in the block *a*, is adapted to engage with said ratchet-teeth and to prevent the lever-arm *b* from turning backward.

55 A flexible metallic band composed of two parts or sections *h* and *i* is pivotally attached at one end to the block *a* and at the other end to the lever-head *c*. One part of section *h* of said band is formed with a series of holes *j*, and the other part is provided with a stud or button *k*, adapted to be engaged with any one of said series of holes, so as to vary the length of the band and adapt it to columns of different sizes, as well as to facilitate placing the clamp upon a column. This band may be conveniently attached to the lever-head and block, as shown, by looping its ends around pins *l* and *m*, passing vertically through the recesses in said lever-head and block perpendicular or at right angles to the plane of the loop formed by the band. This mode of attachment enables the band to readily adjust itself to a column when drawn taut around it and permits the necessary movement of the 60 lever-head *c* around its fulcrum or pivot pin *d* in the block *a* to draw the band taut without abruptly bending it.

65 To facilitate holding the block *a* in place and drawing the band taut on a column, the block is provided with a detachable arm or handle *n*, which has a tapered dovetailed shank *o* fitting a corresponding groove or recess *p* in the top of said block, and the lever-arm *b* is 70 provided with a removable tubular extension *q* or handle *r*.

75 To apply the clamp to a column, the stud or button *k* on one part of the flexible band is disengaged from the other part. The band is then placed around the column, and the pawl *f* being thrown back the lever *b* is turned toward it to separate the end of the band attached thereto from the end of the band attached to the block *a*. The stud or button *k* is engaged with the hole *j*, to which it comes 80 nearest when the band is drawn around the column. The arm or handle *n* being attached to the block *a* and held in one hand and the tubular extension or handle *q* being placed on the lever-arm *b* and held in the other hand, 85

the lever *b* is turned away from the handle *n*, thereby drawing the band taut upon the column and binding its staves or sections firmly together. The pawl *f*, having been turned 5 into position to engage with the ratchet-teeth *e* on the lever-head *c*, prevents said lever-head from turning backward, and thus holds the band taut upon the column, freeing the hands 10 of the operator and permitting the handles *n* and *q* to be removed out of the way.

Various changes in minor details of construction may be made without departing from the principle and intended scope of my invention.

15 I claim—

1. In a column-clamp the combination of a block provided with a handle, a lever fulcrumed to said block, and a flexible metallic band attached at the ends to said block and 20 lever and forming a loop in a plane at right angles to the fulcrum of said lever, substantially as described.

2. In a column-clamp the combination of a block provided with a handle, a lever fulcrumed to said block, and a flexible metallic band composed of detachably and adjustably 25 connected parts attached, one to said block and the other to said lever, and forming a loop in a plane at right angles to the fulcrum of 30 the lever, substantially as described.

3. In a column-clamp the combination of a block provided with a detachable handle, a lever fulcrumed to said block and provided with a removable extension, and a flexible 35 band attached at one end to said block and at the other end to said lever, substantially as described.

4. In a column-clamp the combination of a block provided with a detachable handle, a

lever fulcrumed to said block, a flexible metallic band attached at one end to said block and at the other to said lever and forming a loop in a plane at right angles to the fulcrum of said lever, and means for holding said lever against backward movement when said band 45 is tightened on a column, substantially as described.

5. In a column-clamp the combination of a block provided with a handle, a metallic lever fulcrumed to said column, a flexible metallic 50 band composed of detachably and adjustably connected parts attached one to said block and the other to said lever and forming a loop in a plane at right angles to the fulcrum of said lever, and a pawl and ratchet adapted to 55 hold said lever against backward movement when the band is tightened on a column, substantially as described.

6. In a column-clamp the combination of a block provided with a detachable handle, a lever fulcrumed to said block and provided with a removable extension and with ratchet-teeth, a flexible metallic band composed of detachably and adjustably connected parts which are attached, one to said block and the other 65 to said lever and form a loop in a plane at right angles to the fulcrum of said lever and a pawl pivoted to said block in position to engage with said teeth and prevent backward movement of said lever when the band is tightened 70 on a clamp, substantially as described.

In witness whereof I hereto affix my signature in presence of two witnesses.

JOHN BUFFELEN.
